UNITED STATES PATENT OFFICE

2,341,002

APPARATUS FOR SHAPING TUBULAR BLANKS

Andrew J. Vollrath, Sheboygan, Wis., assignor to
Polar Ware Company, a corporation of Wisconsin

Application March 5, 1942, Serial No. 433,420

5 Claims. (Cl. 113—44)

My invention relates more particularly to apparatus for shaping, by means of fluid under pressure, hollow blanks, especially metal, into hollow articles of the desired shape, as for example articles having portions of larger diameter than the blank such as in the case of teapot bodies, bowls, etc.

My objects generally stated are to provide improvements in such apparatuses to the end that the articles may be more speedily produced and be more satisfactory, and the apparatuses will be adapted to better perform the work for which they are provided; be simplified in construction and positive in operation. Other and more specific objects will be manifest from the following description.

Referring to the accompanying drawings:

Figure 1 is a plan view of apparatus embodying my invention, the ram, forming a part of the apparatus, being omitted.

Figure 2 is a plan view of the apparatus with certain of the upper parts thereof removed.

Figure 3 is an enlarged sectional view of the apparatus, the section being taken at the line 3—3 on Fig. 1 and viewed in the direction of the arrows, showing the parts of the apparatus in one position.

Figure 4 is an enlarged fragmentary sectional view of the portion of the apparatus shown in Fig. 2, the section being taken at the line 4—4 on Fig. 2 and viewed in the direction of the arrows; and

Figures 5, 6 and 7, views like Fig. 3 and of the structure shown therein, illustrating the parts of the apparatus in certain positions occupied by them in the operation of forming an article.

The apparatus shown comprises a base 8 from the center of which a stationary cylindrical post 9 secured thereto, rises, the upper and lower ends of the post being of reduced diameter as represented at 10 and 11, respectively, affording upper and lower annular shoulders 12 and 13, the post 9 bearing at its lower shoulder 13 against the upper central surface of the base 8.

The shoulder 12 forms an annular seat for a gasket 14 encircling the reduced portion 10 of the post 9, the gasket 14 being superposed by a cylindrical sleeve 15 encircling, and vertically slidable on, the reduced upper end 10 of the post and projecting above the upper end of the latter, the outside diameter of the sleeve 15 being the same as the diameter of the intermediate portion 16 of the post 9. The interior surface of the sleeve 15 at its upper end flares upwardly as shown at 17 and the upper end of its wall is

ported at diametrically opposite points as indicated at 18. A set screw 19 carried by the sleeve 15 and extending into a longitudinal key way 20 in the post 9 serves to hold the sleeve to a straight line movement and prevents accidental separation of the sleeve from the post.

The upper surface of the base 8 contains an annular recess 21 concentric with the post 9, in which a plate 22 in the form of an annulus is located and vertically movable. The plate 22 is guided in its movements by headed studs 23 depending from the plate 22 and slidable in openings provided in the base 8, the heads 24 of the studs being disposed in recesses 25 in the base 8. Coil springs 26 interposed between the base 8 and the plate 22 and located in sockets 27 and 28 in these two parts, yieldingly maintain the plate 22 in the elevated position shown in Figs. 3 and 7 for a purpose hereinafter explained, in which position the heads 24 of the studs 23 bear against the top walls of the sockets 25.

The apparatus also comprises a die-proper 29 shown as of general frusto-conical form and formed of two sections 30 and 31 of identical shape, each forming one-half of the die proper, and together forming a die cavity 32 corresponding in contour to the shape desired of the article to be produced.

The die sections 30 and 31, which superpose the plate 22, are secured to levers 33 and 34, respectively, pivoted at 35 and 36 to the plate 22 and swingable on these pivots into and out of the die-closed position shown by dotted lines in Fig. 1, in which position the opposite end portions of the levers 33 and 34 are entered between keeper bars 37 and 38 secured between their ends to the plate 22, as indicated at 39 and 40, to prevent accidental displacement of the die-sections 30 and 31.

The apparatus also comprises a vertically movable female ram 41 disposed in vertical alinement with the die proper 29 when the latter is in closed position. The ram 41, which may be reciprocated by any suitable means (not shown), contains a downwardly facing cavity 42 of a contour adapting it to fit the contour of the die proper 29, whereby when the ram is lowered upon the die proper it will prevent the spreading apart of the die sections 30 and 31, the ram in this position being spaced from the plate 22, and its movement downwardly forcing the assembly formed of the die proper 29 and plate 22, downwardly against the resistance of the springs 26.

It may here be stated that the blank, repre-

sented at 43, from which the article is to be made is in the form of a cylinder having one end closed as shown at 44 in Figs. 3 and 5 and it is assembled with the apparatus by sliding it at its open end over the sleeve 15 and post 9, with which the blank has a sliding fit, to the position shown in Fig. 3; the ram 41 being in raised position as shown in Fig. 7 and the die sections 30 and 31 spread apart as shown by full lines in Fig. 1.

The blank 43 is deformed to conform it to the contour of the die-cavity 32 by means of fluid under pressure, preferably oil under high pressure, and of a character having high lubricating properties, introduced into the blank 43 between the blank and the sleeve 15.

Provision is made for so applying the fluid by providing a passage 45 in the post 9 which opens at its lower end into a pipe 46 which would lead to a suitable supply of fluid under pressure, and at its upper end into the sleeve 15 from which it passes through the ports 18 into the blank 43 between the side wall thereof and the sleeve 15.

In the use of the apparatus the operator, having applied the blank 43 to the position therein as above explained, closes the die-proper 29 about the blank as shown in Fig. 3 and by dotted lines in Fig. 1. He then operates the ram 41 to force it downwardly first to engage and encompass the closed die sections 30 and 31 (Fig. 3) and then to force these die sections downwardly, and with these sections, the plate 22, against the resistance of the springs 26 to the position shown in Fig. 5, the lower ends of the die sections in closed position closely fitting the blank. In this movement of the ram 41 the top wall 47 of the die-cavity 32, which in the normal position of the parts is spaced from the closed end 44 of the blank, is forced downwardly against the closed end of the blank and this downward force is exerted on the sleeve 15 moving it downwardly thereby compressing the gasket 14 between the shoulder 12 and the sleeve 15, causing the gasket to expand laterally and produce a tight joint between the gasket and the side wall of the blank to seal this joint against leakage therethrough of the actuating fluid to be applied for deforming the blank.

The operator thereupon introduces the fluid under pressure into the blank 43 through the course as above described, which deforms the blank into the shape shown in Fig. 6, the article thus deformed to the desired shape being indicated at 48. He then closes the fluid course to the source of supply, raises the ram 41 as shown in Fig. 7 and swings the die-sections 30 and 31 to spread condition as shown by full lines in Fig. 1 to permit the formed article to be removed from the apparatus.

The initial upward movement of the ram 41 permits the springs 26 to return the die-proper 29 and the plate 22 to the normal raised position (Fig. 7) which slides the formed article 48 on the post 9 and sleeve 15 to the elevation shown in this figure, in which position the lower end of the article only partially overlaps the gasket 14, permitting the article to be lifted clear of the sleeve 15 after the die sections 30 and 31 have been swung to open position.

To properly conduct the spent fluid from the apparatus an annular opening 49 is provided around the post 9 which opens into the recess 21 in the base 8, the recess 21 being provided with an annular series of radial passages 50 opening at opposite ends, respectively, into the recess 21 and into an annular gutter 51 provided on the base 8 and having a discharge pipe 52.

The gasket 14 may be made of any suitable material adapted, under the pressure exerted by the ram 41, to distort sufficiently into engagement with the side wall of the blank 43 to form a joint therewith sufficiently tight to hold the high pressure of the fluid used for deforming the blank.

By way of example it has been found that where an article is to be formed of the shape shown, which forms a tea-pot body, utilizing a blank 43 of $2\frac{1}{2}$ inches external diameter and formed of 20 gage stainless steel, the gasket 14 may be formed of rubber of such resiliency as to have a Durometer reading of about 70, the gasket, by way of example, being normally (Fig. 3) of $2\frac{1}{2}$ inches outside diameter and approximately $\frac{3}{4}$ inch thick and of approximately $\frac{1}{2}$ inch cross-sectional width and in the compressing operation being compressed from about $\frac{1}{8}$ inch to $\frac{1}{16}$ inch, the pressure of the fluid supplied for shaping the blank being approximately 5900 lbs. per sq. inch and the pressure exerted by the ram 41 being from about 400 to 600 lbs. per square inch.

Under some conditions it may be desirable or necessary to perform the article-shaping operation by successive steps in the application of the fluid under pressure, increasing the pressure for each subsequent step, the partially deformed blank being removed and annealed prior to each subsequent step to permit of the better drawing of the blank. In the case of the particular example above given it has been found desirable to apply the fluid under pressure by a two-step operation with an intermediate annealing operation, the pressure of the fluid used in the first step of the operation being, by way of example, about 3000 lbs. per square inch and in the second step of the operation being, by way of example, about 5900 lbs. per square inch.

As will be understood from the foregoing the lower end of the blank is free to slide upwardly on the post in the deforming of the blank into the die-cavity, which is of decided practical value as thereby such thinning of the metal of the blank as would occur if both ends of the blank were held in fixed position, is avoided.

While I have illustrated and described a particular construction embodying my invention I do not wish to be understood as intending to limit it thereto, as the same may be variously modified and altered and the invention embodied in other forms of structure without departing from the spirit of my invention.

What I claim as new and desire to secure by Letters Patent, is:

55. Article-shaping apparatus comprising a member having a seat for a gasket, a gasket on said seat, a sectional die member having a die-cavity for shaping a tubular blank surrounding said first-named member and gasket, a sleeve 60 slidable on said first-named member against said gasket for forcing said gasket against said blank and means for subjecting the interior of the blank to fluid under pressure for expanding said blank into said die-cavity.
65. Article-shaping apparatus comprising a member having a seat for a gasket, a gasket on said seat, a sectional die member having a die cavity for shaping a tubular blank surrounding said first-named member and gasket, a sleeve 70 slidable on said first-named member against said gasket for forcing said gasket against said blank, said members being relatively movable and said die member having a portion which, in the relative movement of said members, forces said sleeve 75 against said gasket, and means for subjecting

the interior of the blank to fluid under pressure for expanding said blank into said die-cavity.

3. Article-shaping apparatus comprising a member having a seat for a gasket, a gasket on said seat, a sectional die member having a die cavity for shaping a tubular blank surrounding said first-named member and gasket, a sleeve slidable on said first-named member against said gasket for forcing said gasket against said blank, said members being relatively movable and said die member having a portion which, in the relative movement of said members, forces said sleeve against said gasket, means for subjecting the interior of the blank to fluid under pressure for expanding said blank into said die-cavity, and means yieldingly resisting relative movement of said members in the gasket-expanding operation.

4. Article-shaping apparatus comprising a member having a seat for a gasket, a gasket on said seat, a sectional die member having a die-cavity for shaping a tubular blank surrounding said first-named member and gasket, a sleeve having its wall ported, slidable on said first-named member against said gasket for forcing

said gasket against said blank, and means for subjecting the interior of the blank to fluid under pressure for expanding said blank into said die-cavity and entering said blank through the ported wall of said sleeve.

5. Article-shaping apparatus comprising a member having a seat for a gasket, a gasket on said seat, a sectional die member having a die cavity for shaping a tubular blank surrounding said first-named member and gasket, said blank having a portion at one end extending crosswise of said blank, a sleeve slidable on said first-named member against said gasket for forcing said gasket against the side wall of said blank, said members being relatively movable and said die-member having a portion which, in the relative movement of said members, engages said portion of said blank which laps an end of the sleeve and forces said sleeve against said gasket and means for subjecting the interior of the blank to fluid under pressure for expanding said blank into said die-cavity.

ANDREW J. VOLLRATH.
